Application October 21, 1955, Serial No. 38,518

Term of patent 3½ years

(Cl. D33—19)

FIG. 5

FIG. 3.

FIG. 2.

FIG. 4.

Fig. 1 is a perspective view of a storage cabinet, showing my new design;

Fig. 2 is a top plan view of the storage cabinet of my new design;

Fig. 3 is a vertical, sectional view taken on the broken line 3—3 of Fig. 1;

Fig. 4 is a vertical, sectional view taken on the broken line 4—4 of Fig. 1; and

Fig. 5 is a perspective view of one of the drawer units removed from the cabinet.

The back of the storage cabinet is not shown in elevation because it is flat and of conventional configuration.

I claim:

The ornamental design for a storage cabinet, as shown and described.
